UNITED STATES PATENT OFFICE

ANDREW C. KAPPES, OF CHICAGO, ILLINOIS, ASSIGNOR TO WM. WRIGLEY JR. COMPANY, OF CHICAGO, ILLINOIS, A CORPORATION OF DELAWARE

CONFECTION PACKAGE

Application filed March 14, 1929. Serial No. 346,963.

This invention relates to improvements in confection packages, and more particularly to packages for lozenge shaped chewing confections.

5 It is customary to package these confections in a wrapper of paraffine paper, sealing the flaps by the application of heat to make the package moisture-proof. Moreover, the confections are packed in rows, the several pieces 10 being arranged in flatwise contact. In a patent granted to Andrew C. Kappes on August 25, 1925, No. 1,550,966, a package is disclosed in which the wrapper of paraffine paper is pressed inwardly between the several pieces 15 with the application of heat, thereby forming a series of corrugations surrounding the package from end to end. The purpose of these corrugations is to provide a retaining recess for each individual piece of confection 20 so that upon opening the package at one end and removing the endmost piece, the remaining pieces will not be dislodged and fall out when carrying the package in the pocket.

In addition to the paraffine wrapper, the 25 complete package includes an outer band or label wrapped around the package lengthwise with its end portions overlapping on one face of the package and sealed.

The present improvement has to do with 30 the application of this outer band, so as to aid in retaining the inner wrapper in its original corrugated form and to prevent its own displacement from the package.

A package embodying the novel features 35 is disclosed in the accompanying drawings, in which

Figure 1 is a perspective view of a package before the outer band has been applied showing the corrugated appearance.

40 Figure 2 is a perspective view of a single lozenge shaped confection.

Figure 3 is a perspective view of a package with the outer band partially folded about it and ready for sealing; and

45 Figure 4 is a perspective view of the completed package.

For the purpose of this disclosure, the package consists of ten lozenges A arranged edgewise and face to face in a row. These lozenges 50 are somewhat rounded at their edges and cor-

ners as shown in Figure 2, and are first enclosed in a wrapper B of paraffine impregnated paper, with the end portions folded inwardly and over each other in the usual manner. As thus arranged and wrapped, 55 depressions or crevices are formed between the edges of the lozenges into which the surrounding wrapper is depressed, giving the package the accordion appearance shown in Figure 3.

As already suggested, the package is subjected to pressure and heat while the wrapper is being applied and after the end portions have been folded this being usually accomplished by advancing the packages 60 through or between electrically heated dies having corrugated surfaces.

The sealed package is then banded by an outer wrapper or band C, consisting preferably of a printed label. In applying this band, the edge portions c' and c preferably overlap throughout one of the wider faces of the package, the undermost edge portion c' 65 being first corrugated to conform with the corrugations in the surface of the package beneath, as shown in Figure 3.

Before the top flap or portion c is brought over for sealing, relatively thin lines of adhesive are applied along the crest of the elevated portions of the lower flap, as at d. Thus 70 with the final sealing operation, the adhesion between the two flaps c and c' is along a series of parallel lines, which act to retain the corrugated form of the under flap, while the upper flap remains smooth thereby 75 sealing the undulations beneath.

From the foregoing it is manifest that the 80 corrugated under flap c' becomes relatively fixed in that form, by reason of its several points or lines of adhesion with the upper flap, and the fact that the latter is flat and un-corrugated, thus acting as a tension member to retain the corrugations in the under flap, which in turn serve to stiffen or reinforce the corrugations in the paraffine wrapper with which they register. The result 85 therefore is that the entire package is stiffened lengthwise and against elongation, as otherwise there is only the stiffness of the paraffine impregnated wrapper to maintain the corrugated 90 package.

55 60 65 70 75 80 85 90 95 100

gations. Furthermore, the particular manner of binding and sealing the outer wrapper or band, holds the latter in place, preventing it from sliding endwise and thus becoming displaced.

5 While in the preferred form illustrated, glue is shown as applied at *d* to each of the high points of the corrugation, it is manifest that similar results can be obtained by applying glue to fewer such points, as for instance to every other high spot, or every third high spot.

I claim as my invention:

1. A confection package comprising a row 15 of lozenge shape confections having spaces between their edges, a wrapper enclosing said confections and depressed within the spaces to form corrugations extending around the package, and an outer wrapper 20 surrounding said package with its opposite marginal portions overlapping on one face thereof, the underlapping portion being corrugated to conform to the corrugated surface beneath and the overlapping portion being 25 glued thereto along the elevated portions of said corrugations.

2. A confection package comprising a plurality of lozenge shaped confections having rounded edges and arranged face to face, a 30 wrapper of moisture-proof paper enveloping said confections and sealed with the portions thereof intermediate the ends of the package depressed into the spaces between said confections on all sides, and an outer wrapper 35 surrounding the sealed package lengthwise and having one marginal portion corrugated to conform to the surface beneath, and the other marginal portion overlapping said first mentioned marginal portion and sealed flat- 40 wise along the elevated portions thereof.

3. A confection package comprising a plurality of lozenge shaped confections arranged face to face and shaped to provide recesses between adjacent confections, a 45 wrapper of paraffine paper enveloping said confections and sealed at each end, with the paper pressed into the spaces between the individual confections throughout the central portion of the package to form transverse 50 corrugations on each face thereof, and an outer wrapper surrounding the sealed package with its marginal portions overlapping on one face thereof, the underlapping portion being corrugated to conform to the surface of the package beneath and the overlapping portion being smooth and sealed to the elevated areas of said underlapping portion.

4. A method of packaging lozenge-shaped 60 confections having rounded edges, consisting of applying an inner wrapper, depressing said inner wrapper into the spaces between the confections, providing an outer wrapper adapted to surround said package with its 65 opposite marginal portions overlapping on

one face thereof, corrugating the underlapping marginal portion of said outer wrapper to conform to the corrugations in the surface beneath, and sealing the overlapping marginal portion along the elevated portions of the corrugations of said underlapping marginal portion.

5. A method of packaging lozenge shaped confections having rounded edges, consisting of arranging the confections in a row face to face, applying a wrapper of moisture-proof paper around said confections, depressing the wrapper into the spaces between said confections and sealing the ends thereof by the application of pressure and heat, surrounding the sealed package lengthwise with an outer wrapper, corrugating one marginal portion of said outer wrapper to conform to the surface beneath, applying adhesive to the elevated portions only of said corrugated marginal portion, and sealing the other marginal portion flatwise over the same.

Signed at Chicago, Ill., this 11th day of March, 1929.

ANDREW C. KAPPES.
